US0D1013104S

(12) **United States Design Patent** (10) Patent No.: **US D1,013,104 S**
(45) Date of Patent: ** *Jan. 30, 2024

(54) **HAND SHOWER**

(71) Applicant: **HANSGROHE SE**, Schiltach (DE)

(72) Inventors: **Matthias Oesterle**, Winterbach (DE);
Marco Flraig, Stuttgart (DE)

(73) Assignee: **Hansgrohe SE**, Schiltach (DE)

(*) Notice: This patent is subject to a terminal disclaimer.

(**) Term: **15 Years**

(21) Appl. No.: **29/779,656**

(22) Filed: **Apr. 20, 2021**

(51) LOC (14) Cl. **23-01**

(57) **CLAIM**

The ornamental design for a hand shower, as shown and described.

DESCRIPTION

FIG. 1 is a perspective view of a hand shower showing our design;

FIG. 2 is a front elevational view;

FIG. 3 is a rear elevational view;

FIG. 4 is a right side elevational view;

FIG. 5 is a left side elevational view;

FIG. 6 is a top plan view; and,

FIG. 7 is a bottom plan view.

The dashed broken lines depict portions of the hand shower that form no part of the claim.

1 Claim, 7 Drawing Sheets
